(57) **CLAIM**

The ornamental design for a threaded storage container lid, as shown and described.

DESCRIPTION

FIG. 1 is a perspective view of a threaded storage container lid showing our new design;

FIG. 2 is front view of the container lid;

FIG. 3 is a top view of the container lid; and,

FIG. 4 is a bottom view of the container lid.

The rear of the container lid and both the right and left sides of the container lid are identical to the front of the container lid depicted in FIG. 2.
